C. S. BURTON,
REBOUND CHECK FOR VEHICLES,
APPLICATION FILED SEPT. 8, 1919.

1,337,996.

Patented Apr. 27, 1920.

UNITED STATES PATENT OFFICE.

CHARLES S. BURTON, OF OAK PARK, ILLINOIS.

REBOUND-CHECK FOR VEHICLES.

1,337,996.

Specification of Letters Patent. Patented Apr. 27, 1920.

Application filed September 8, 1919. Serial No. 322,514.

To all whom it may concern:

Be it known that I, CHARLES S. BURTON, a citizen of the United States, and a resident of the village of Oak Park, in the 5 county of Cook and State of Illinois, have invented certain new and useful Improvements in Rebound-Checks for Vehicles, of which the following is a specification, reference being had to the accompanying drawings, forming a part thereof.

The purpose of this invention is to provide an improved device for absorbing the shock to which the bodies or load carrying members of a vehicle, particularly a spring 15 supported vehicle, are exposed from the up and down movements of the wheels and axles resultant from passing over irregularities in the road bed or the like. It consists in the elements and features of construction shown and described, as indicated 20 in the claims.

In the drawings:

Figure 1 is a trans-axial section of a device embodying this invention, the parts 25 within the inclosing case being shown in elevation.

Fig. 2 is an edge elevation of the same.

Fig. 3 is a section at line 3—3, on Fig. 1.

Fig. 4 is a partial side elevation of the 30 case.

The device shown in the drawings comprises a casing consisting of a laterally chambered or cup-shaped member, 1, and a closure plate, 2, for closing the otherwise 35 open side of the case, two complementary members, 3—3, together forming what is substantially a drum, upon which there is coiled a flexible friction band, 4, one end of the band being secured to one of 40 said complementary members and the band being then coiled several times around the drum comprising these two members and the free end passed out through an aperture, 1^a, in the case, the latter having its peripheral flange extended tangentially at the side at which the aperture, 1^a, is seen clearly in Fig. 1. The two complementary members, 3—3, have each a cylindroidal surface, 3^a, said two surfaces being complementary to 45 each other for the purpose of together forming a nearly complete cylindrical drum, that is, complete excepting as to two intervals or apertures between the said two complementary members. Said complementary members, 3—3, are mounted on 50 pivots, 5—5, which also constitute bolts for

securing together the two case members, and securing the case to the vehicle, by engaging any convenient part of the body or load-carrying members of frame structure indicated in dotted line at 10. Each of the members, 3—3, has extending from its heel, that is, beyond its fulcrum on its pivotal side a lug, 7, and these two lugs are connected together by the contractile or stretchable spring, 8, which operates to normally hold the two members 3—3, expanded,—that is, spread apart,—to a limit determined only by the capacity of the case or by the contractility of the spring; and the spring 70 60 65 75 80 85 90 95 100 105 110 yieldingly resists the contraction of the drum closing or folding together of the two members, 3—3. The flexible friction band, 4, has its free end connected loosely to the axle of the vehicle or to some part which is fixed with respect to the vehicle support, for which purpose it is provided with a loop or eye 11.

At the lowest position of the body with respect to the axle,—that is, the position 80 reached under a maximum load or under shock,—the friction band, 4, is coiled snugly and smoothly about the drum comprising the two members, 3—3, the latter being expanded to what may be considered the maximum size of drum, thus taking up the maximum amount of the flexible band in the coils which encompass the drum. Upon reaction from the shock by which the load is depressed, or upon release from the load 90 or a part thereof, the rise of the body caused by spring support compels the uncoiling of some portion of the flexible friction band from the drum. As this can be accomplished only by the frictional slipping 95 of the coils in the band one upon another and contraction of said coils around the two members constituting the drum tending to fold said two members together against the resistance of the spring, 8, the frictional resistance of the coils of the friction band upon each other, and of the inner coil upon the cylindroidal surfaces of the drum members, retards this reaction, preventing excessive recoil, and thereby preventing the back-and-forth rebound which, in the absence of some damping or shock absorbing device, usually results from the shock due to irregularities in the road bed or abrupt obstruction encountered by the 110 wheels.

It has heretofore been proposed to accom-

plish this or like result by complementary cylindroidal members constituting a drum, which are held directly apart from each other for expanding the drum to take up 5 the coils of a friction band encompassing the drum: but in such a device the frictional drag of the friction band upon the cylindroidal members being in part directly transverse to the movement of said members with 10 respect to each other, and as to the remainder being equally divided or balanced for drawing them together and pulling them apart, the net effect of the drag is a pull upon said members directly transverse to 15 their movements with respect to each other, thereby tending to embarrass that movement. In the construction herein shown, the drag of the friction band on the two members of the drum, that is the pull which 20 uncoils the band, operates on the cylindroidal periphery of the drum members in a direction which swings them about their pivots in the inward-folding or drum-reducing movement, and said drag therefore assists instead of embarrassing the diameter-reducing 25 movement of the drum members. This construction, therefore, makes the resistance of the spring the measure of the pressure by which the several coils of the band are held 30 in frictional contact with each other and with the drum members for causing the desired friction by which the recoil is damped or retarded, and avoids adding to said spring's resistance,—which is calculable 35 and uniform,—any other frictional or in- calculable resistance, such as results in the previous construction referred to from the transverse drag upon the drum members when they are mounted for direct movement

toward and from each other radially with respect to the coil: and the invention claimed herein consists substantially in the manner of mounting and connecting the drum members so as to produce this result.

I claim:

1. In a device for the purpose indicated, in combination with two members having complementary curved surfaces which together constitute substantially a cylindrical drum; a support to which said two members are pivoted near their ends respectively, at substantially diametrically opposite points with respect to the cylindrical contour defined by said complementary surfaces; a spring connecting the complementary members for yieldingly expanding or spreading apart their complementary surfaces, and a flexible friction band coiled around said members on their said complementary surfaces.

2. A structure defined in claim 1 foregoing, the complementary members being extended beyond their supports, and the spring being a contractile spring connecting said extensions for reaction to spread said members.

3. In the construction defined in claim 1, the support consisting of one side plate of a casing for inclosing the complementary members, the spring and the flexible friction band; said case comprising also an opposite plate, and the two plates being tied together for inclosing said part by the pivots of the two complementary members.

In testimony whereof I have hereunto set my hand at Chicago, Illinois, this 3rd day of September, 1919.

CHARLES S. BURTON.
